UNITED STATES PATENT OFFICE.

ALFRED L. EUSTICE, OF CHICAGO, ILLINOIS.

METHOD OF MAKING FUSE LINKS.

1,426,827.

Specification of Letters Patent. Patented Aug. 22, 1922.

Application filed March 7, 1918. Serial No. 220,964.

To all whom it may concern:

Be it known that I, ALFRED L. EUSTICE, a citizen of the United States, and resident of Chicago, in the county of Cook and State of Illinois, have invented certain new and useful Improvements in Methods of Making Fuse Links, of which the following is a specification.

This invention relates to a method of making fuse links.

One of the objects of the invention is to facilitate the making of fuse links.

Another object is to improve the method of making fuse links in a manner to meet commercial requirements.

Generally speaking these and other objects are accomplished by use of the method consisting first in providing a plurality of terminal blanks and a fusible blank, connecting the blanks to form a single blank, and then cutting the same in accordance with requirements.

The invention is illustrated on the accompanying sheet of drawings in which—

Figure 1 is a perspective view of the terminal blanks and fusible blank, provided with cooperating bent edges in engagement with each other.

Figure 2 is a side elevation of the completed fuse link, the blanks having their edges pressed into a locking engagement with each other and cut in accordance with requirements, and

Figure 3 is a plan view of a plurality of completed fuse links, stamped from the completed blank.

The novel features of the invention will be apparent from the following description and drawing and will be particularly pointed out in the appended claims.

By the use of my method I endeavor to make a relatively large number of fuse links from a unified blank formed from three separate blanks, two of which are terminal blanks and the other of which is the fusible blank.

By referring to the figures on the drawings, it will be noted that I have provided the three blanks 10, 11 and 12, the first two of which preferably are of copper and the last preferably is of zinc. These blanks are taken from stock in the form of straight ribbons. One of the longitudinal edges 13 of each of the terminal blanks is bent, preferably at right angles to the main body portion. The two longitudinal edges 14 of the

fusible blank 12 are bent preferably at right angles to the main body portion of the blank to form, in effect, a channel member. The bent over edges 13 and 14 are then brought into overlapping engagement with each other whereupon the blanks are placed in suitable dies and pressed into locking engagement with each other, as shown in Fig. 2 of the drawing. As shown in this figure the bent edges 13 and 14 of the blanks are pressed into interengaging hook portions and when pressed sufficiently will form a good mechanical as well as an electrical connection between the blanks. To improve the electrical connection of the unified blank, the interengaging hook portions or joints between the original blanks 10, 11 and 12 are soldered. The completed unified blank 15 is then run through the stamping machine whereupon the fuse links 16 are stamped out. It will be noted that each fuse link includes two terminal members 17 and 18 and the fusible member 16, the first terminal member being provided with a longitudinally arranged slot 19 and the other terminal member having a laterally extending slot 20 for securing the same to other terminal members. The fusible member 16, it will be noted, is of the drop-out section type, the link being provided with laterally arranged stamped out portions 21 to form relatively narrow necks 22, to cause the melting of the link at the neck portions, whereby the intermediate portion of the member 16 will drop out of mechanical and electrical engagement with the other parts of the link.

By means of this process, fuses may be provided in a simple manner from a unified blank composed of a plurality of separate blanks and in a manner to meet commercial requirements.

It is my intention to cover all modifications of the invention falling within the scope of the following claims.

I claim:

1. The method of forming fuse links consisting first in providing a plurality of terminal blanks and a fusible blank, said fusible blank being flanked by said terminal blanks, then bending the edges of said blanks and pressing the same to form mechanically secure connections therebetween thereby providing a unified blank, then perfecting the electrical connection by soldering, and then stamping fuse links from the unified blank, transversely of said bent edges to produce

links having a fusible central portion and end portions cut from said terminal blanks.

2. The method of forming fuse links consisting first in providing a plurality of terminal blanks and a fusible blank, said fusible blank being flanked by said terminal blanks, then bending the edges of said blanks and pressing the same to form interlocking connections therebetween thereby providing a unified blank, and then stamping the

fuse links from the unified blank, transversely of said bent edges to produce links having a fusible central portion and end portions cut from said terminal blanks.

Signed at Chicago, Illinois, this 21st day 15 of February, 1918.

ALFRED L. EUSTICE.
